CIGARETTE PACKAGE

Alfred German Rose, Gainsborough, England, assignor to Rose Brothers (Gainsborough) Limited, Gainsborough, England, a British company

Application August 1, 1935, Serial No. 34,198
In Great Britain April 25, 1934

2 Claims. (Cl. 229—51)

This invention relates to packages of the kind comprising a carton, group of cigarettes or the like enclosed within a wrapper of paper, transparent cellulose material or the like which wrapper has folded and sealed flaps. The object of 5 the present invention is to provide means by which the wrapper of such package may be removed easily.

According to the present invention a package 10 of the above kind is provided with a strip or ribbon extending from side to side of the wrapper, secured thereto along its length and terminating at one end near the margin of an outer sealed flap of the wrapper. The invention is particularly applicable to packages of the kind wherein 15 the wrapper is folded into U-shape about one end and two sides of the contents of the package, side flaps are folded in and sealed and finally end flaps are folded in and sealed and 20 the strip or ribbon extends, in such a package, from the outer end flap around the package to the inner end flap.

The wrapper may be removed from a package 25 in accordance with this invention by gripping the end of the strip or ribbon at the said outer sealed flap and pulling it so that it rips the wrapper and renders the wrapper easy to remove. To facilitate the tearing of the wrapper, the said 30 outer sealed flap may be slit at each side of the strip or ribbon. For this purpose also the strip or ribbon may be secured to the inner surface of the wrapper.

One embodiment in accordance with this invention will now be described, by way of example 35 only, with reference to the accompanying drawing, in which:

Figure 1 shows a package in accordance with this invention,

Figure 2 shows the package during the process 40 of opening it, and

Figure 3 is a section on the line III—III of Figure 1.

The package comprises a carton 10 (Figure 3) 45 of the shell and slide type but the precise nature of the contents of the package is immaterial. The carton 10 is enclosed in a wrapper 11, which may be of paper, cellulose or other suitable material. The wrapper 11 is folded about the carton 10, in the known manner, by first folding it 50 about the rear end and top and bottom sides (as seen in Figures 1 and 2) and then folding in side flaps on the two vertical sides of the carton. The side flaps are sealed with adhesive. The wrapper then forms a pouch about the car- 55 ton and is closed by folding in side tucks 12 and

an inner end flap 13 and an outer end flap 14. The flaps 13 and 14 are sealed by adhesive but the extreme margin 15 of the outer flap 14 is not sealed down and preferably extends as shown beyond the edge of the end of the package 5 so that it can be more readily grasped by the fingers of a person opening the package.

A strip or ribbon 16 is secured by a suitable adhesive to the inside of the wrapper and extends from the margin of the outer flap 14 across 10 the front end face, top face, the rear end face and the bottom face of the package to the margin of the inner end flap 13. This strip or ribbon may be formed of paper, thin cardboard, woven fabric, cellulose material or the like. The 15 outer end flap 14 is slit at 17 on either side of the strip 16.

To remove the wrapper, the outer end 18 of the strip 16 together with the portion of the outer flap 14 adjacent thereto is gripped by the 20 person opening the package. This person then pulls on the strip ripping the wrapper 11 as shown in Figure 2. The strip 16 together with a portion of the wrapper 11 to which it is secured can be completely ripped from the package leaving 25 the wrapper in the form of two halves which can be readily removed sideways from the package. The strip 16 re-enforces the wrapper and ensures that a complete circumferential strip of the wrapper is removed and that the two tear 30 lines do not converge to a point before they have completely encircled the package.

In many cases the wrapper is formed of a transparent material such as a cellulose material in order that the contents of the package 35 may be readily seen. In such cases the strip or ribbon is preferably also of a cellulose material and is secured to the wrapper by means of a transparent adhesive. When the wrapper and strip are both formed of a cellulose material 40 they may be secured together by means of a solvent and the term "adhesive" is herein used to include such a solvent.

I claim:

1. A package having a wrapper extending in 45 a continuous manner from one end over the top, around the opposite end and the bottom to the first end, the sides of the package being enclosed by first folding the side flaps at the said opposite end of the package, then the bottom flaps, and 50 then the top flaps, and then enclosing the first end by first folding the side flaps, then the bottom flap and then the top flap over the bottom flap, there being a ripping ribbon secured to the inside of the wrapper, extending from the edge 55

of last mentioned top flap around the entire box to the last mentioned bottom flap whereby the entire wrapper may be separated into two parts from the end having four folded flaps.

- 5 2. A package having a wrapper extending in a continuous manner from one end over the top, around the opposite end and the bottom to the first end, the sides of the package being enclosed by first folding the side flaps at the said opposite 10 end of the package, then the bottom flaps, and then the top flaps, and then enclosing the first end by first folding the side flaps, then the bot-

tom flap, and then the top flap over the bottom flaps, there being a ripping ribbon secured to the inside of the wrapper, extending from the edge of the last mentioned top flap around the entire box to the last mentioned bottom flap whereby the entire wrapper may be separated into two parts from the end having four folded flaps, there being a slit at each side of the ribbon extending inwardly from the edge of the last mentioned top flap inwardly for a short distance. 10

ALFRED GERMAN ROSE.
